J. H. ALTER.

CUT OFF ADJUSTER FOR POWER OPERATED REVERSING GEAR.

APPLICATION FILED FEB. 9, 1918.

1,278,820.

Patented Sept. 17, 1918.

UNITED STATES PATENT OFFICE.

JOHN H. ALTER, OF CONNEAUT, OHIO.

CUT-OFF ADJUSTER FOR POWER-OPERATED REVERSING-GEAR.

1,278,820.

Specification of Letters Patent. Patented Sept. 17, 1918.

Application filed February 9, 1918. Serial No. 316,156.

To all whom it may concern:

Be it known that I, JOHN H. ALTER, a citizen of the United States, residing at Conneaut, in the county of Ashtabula and State of Ohio, have invented a certain new and useful Improvement in Cut-Off Adjusters for Power-Operated Reversing-Gear, of which the following is a full, clear, and exact description, reference being had to the accompanying drawings.

This invention relates to railway locomotives and particularly to the power-operated reversing-gear employed thereon for moving and adjusting the link motion to vary the cut-off and the direction of rotation.

This link motion was originally moved directly by means of a large lever situated in the locomotive cab, but with the increase in the size of locomotives it became difficult and at last impossible even for a strong man to move the parts, particularly when cold, frozen, or rusty. Consequently various mechanisms have been devised for the purpose of effecting this operation by means of steam from the boiler or compressed air from the brake system, this mechanism being controlled by means of a comparatively small lever mounted in the cab in place of the original reverse lever. This small lever is ordinarily movable along a notched sector, the notches being not generally less than about one fourth inch wide and one fourth inch apart in order to afford the strength of construction necessary for a device exposed to such strains and usage as locomotives. Such a construction, however, entails a minimum lever movement of at least one half inch and renders it frequently impossible to adjust the cut off at the proper point where the best performance can be secured, even when the entire mechanism is in the most perfect adjustment; while if the valves or packings of the mechanism are faulty, it is sometimes almost impossible to secure proper running.

The object of my invention is the provision of a simple, strong and rugged device whereby a finer adjustment can be secured; the provision of a device which can be applied without difficulty or expense to locomotives and reversing gear already in operation; the provision of a device of this character which will coöperate with the standard devices already in use and which will permit the operation of those standard devices in their previously intended manner and which

can be used or neglected at will without changing the mode of operation of the previous devices; while further objects and advantages of the invention will become apparent as the description proceeds.

In the drawings accompanying and forming a part of this application, I have illustrated one of the many embodiments whereby my invention may be availed of, although it will be understood that these drawings are illustrative only and not limiting, and that many modifications can be made and that many variations even in the proximate device can be made within the limits of my invention, while the details of the locomotive, reversing gear, etc., are illustrated solely for convenience and may be departed from to any extent. In these drawings Figure 1 is a side view of a locomotive showing a standard type of reversing gear provided with my improvements; Fig. 2 is an enlarged view showing the reversing gear more in detail; Fig. 3 is a detail view taken on the line 3—3 of Fig. 4 and looking in the direction of the arrows; Fig. 4 is a sectional view taken on the line 4—4 of Fig. 3 and looking in the direction of the arrows; and Figs. 5 and 6 illustrate slightly modified embodiments of my invention.

Describing the parts by reference characters 1 represents the horizontal drag link of a locomotive suitably connected to the link motion (not shown) whereby the cut off and direction of operation may be controlled. 2 represents a cylinder carried by the side of the locomotive in a horizontal position and having a piston 3 connected to a piston rod 4 attached to a cross head 5 and also to this drag link whereby it is operated. At one side of this cylinder is located the valve box 6 having therein a slide valve 7 connected to the stem 8 whose outer end is pivoted at 9 to a lever 10 whose opposite end is pivoted at 11 either to the cross head 5 or to a suitable member 12 attached thereto. Between the two ends of the lever there is pivoted at 13 a link 14 whose opposite end is pivoted as at 15 to a lever 16 fulcrumed at 17; and to the upper end 18 of this last lever is articulated the reach rod 19 which extends into the cab. Suitably secured inside the cab is a sector 20 having pivoted thereto a lever 21 whose lower end is connected to the reach rod 19 and whose upper end carries the detent 22 coöoperating with the teeth

23 of the sector. In the present embodiment the reach rod is shown as connected to the lever below the point 24 where it is pivoted to the sector, so that upon the forward movement of the lever handle the reach rod will be pulled rearwardly. This rocks the top of lever 16 to the rear and advances the link 14 carrying with it the slide valve 7. This serves to admit steam or air from the inlet 30 to the rear of the cylinder and places the forward end of the cylinder in communication with the outlet 31 whereupon the piston 3 is advanced, carrying with it the cross head 5 and lever 10, which movement continues until the rocking of the last named lever about the fulcrum 13 restores the slide valve to closed position which normally occurs when the piston reaches a point in the cylinder corresponding to the setting of the lever 21 upon its sector. Normally, the piston moves through a distance three or four times greater than the movement of the lever relatively to its sector; thus if the notches in the sector are one eighth inch wide and the teeth are one eighth in width, the smallest possible movement of the lever is one quarter inch, which corresponds to the movement of the piston of one and one-half to two inches, supposing the device to be in perfect adjustment; while if the pivots are worn or the valve displaced, or the packings leaky, the piston frequently moves a distance varying as much as fifty per cent. more or less than normal.

55 In order to overcome this difficulty and to provide for a more accurate adjustment, I substitute for one of the pivots inside the cab a device including an eccentric part together with means for rotating the part so that, without disengaging the lever from the sector, the reach rod can be shifted through any distance less than that which would correspond to a movement of the lever between adjacent notches of the sector. This device can be applied either to the pivot between the lever and reach rod or to that between the lever and the sector and may be made in any one of several ways.

In Figs. 1 to 4 inclusive I have shown it 50 as located at the junction of the lever and reach rod, and in Fig. 5 I have shown it as located at the other point mentioned. In Figs. 3 and 4, 35 represents a stud having a flange 36 and rigidly clamped to the lever 21 by the nut 37. Journaled on the stud 35 is a hand wheel 38 held in place by the nut 39 and having an eccentric hub 40 which enters an aperture in the reach rod 19 freely. A spring washer 41 is shown between the 60 nut 39 and hand wheel for holding the device from creeping, although this probably is not necessary.

In Fig. 6 the pivot member is made of one integral piece having relatively eccentric parts 44 and 45 separated by a flange 46,

one part entering the aperture freely in a lever 21 the other freely the aperture in reach rod 19. The part 44 is held in place by a washer 47, which may be of friction type, and nut 48; the other part terminates in a 70 squared shank 49 on which is clamped the hand wheel 50.

The device shown in Fig. 6 may be used in place of that illustrated in either Figs. 4 or 5. The total length of the lever 21 is 75 generally between a foot and a foot and a half which brings the hand-grip 38 or 50 in easy reach of the engineer. The parts are strong, rugged and simple and not liable to get out of order; and in case the engine 80 driver prefers not to use them the operation of the locomotive is not disturbed by their presence.

It will be understood that numerous changes, other than those pointed out, can 85 be made within the scope of my invention.

Having thus described my invention, what I claim is:—

1. In a locomotive engine, the combination with power operated reversing gear, of a 90 controlling device comprising a toothed sector, a lever pivoted for movement relatively thereto, a reach rod pivoted to said lever, and means located at one of such pivot points whereby said reach rod can be shifted through a distance less than that which would be produced by a movement of said lever between adjacent notches of said sector.

2. In a locomotive engine, the combination with power operated reversing gear, of a 100 controlling device comprising a toothed sector, a lever pivoted for movement relatively thereto, a reach rod pivoted to said lever, one of such pivots comprising an eccentric member, and means for rotating said member whereby said reach rod can be shifted 105 without moving said lever along its sector.

3. In a locomotive engine, the combination with power operated reversing gear, of a 110 controlling device comprising a toothed sector, a lever pivoted for movement relatively thereto, a reach rod pivoted to said lever, and means operative during the time that said lever is latched to said sector for shifting one of the pivot points whereby said 115 reach rod is moved through a distance less than that which would be produced by a movement of said lever between adjacent notches of said sector.

4. In a locomotive engine, the combination, with power operated reversing gear, of a controlling device comprising a toothed sector, a lever pivoted for movement relatively thereto, a reach rod pivoted to said lever, one of such pivots comprising a pair 120 of relatively eccentric parts, and means for rotating such eccentric part whereby said reach rod will be shifted without moving said lever past the notched edge of said sector.

5. In a locomotive engine, the combination, with power operated reversing gear, of a controlling device, comprising a toothed sector, a lever pivoted for movement relatively thereto, a reach rod pivoted to said lever, one of such pivots comprising a pair of relatively eccentric parts, a hand-grip

carried by the eccentric part for turning the same, and friction means for retaining it in position to which it is turned. 10

In testimony whereof, I hereunto affix my signature.

JOHN H. ALTER.
